CLAIM

The ornamental design for a combined oil drain pan and container, as shown and described.

DESCRIPTION

FIG. 1 is a front, top, right side perspective view of a combined oil drain pan and container showing my new design, on a reduced scale;

FIG. 2 is a front elevational view thereof;

FIG. 3 is a top plan view thereof;

FIG. 4 is a left side elevational view thereof;

FIG. 5 is a bottom plan view thereof; and,

FIG. 6 is a rear elevational view thereof.

FIG. 3

FIG. 2

FIG. 4

FIG. 5

FIG. 6
